UNITED STATES PATENT OFFICE

2,121,281

FAUCET

José Vidal Bosque, Habana, Cuba

Application July 27, 1936, Serial No. 92,871

1 Claim. (Cl. 277—42)

This invention refers to refrigerators, its main purpose being to provide means through which the cooling water tank may be detached from the cock therein; said arrangement allows to withdraw the tank without having to disconnect the same from the cock.

A further object of the invention is to provide means to avoid any loss of cold due to this novel arrangement of the refrigerator.

10 Referring to the drawings:

Figure 1 is a front elevation of the improved refrigerator.

Figure 2 is a front elevation of said refrigerator shown with its door open.

15 Figure 3 is a partial sectional view through line 3—3 of Figure 1.

Figure 4 is another sectional view according to line 4—4 of Figure 2.

20 Figure 5 is a sectional view in an enlarged scale showing the improvements of the present invention.

Figure 6 is a cross sectional view through line 6—6 of Figure 5.

25 Figures 7 and 8 are sectional views in detail of the different parts of the invention; the Figure 8 showing a modified embodiment of same.

Figure 9 is a sectional view of an operative position; and

30 Figures 10, 11 and 12 are perspective detail views of the different parts embodying the invention.

Numeral 1 refers to a refrigerator cabinet and 2 the door therein. Said door has a horizontal opening through which bushing 3 fits, having an integral washer 3'. The bottom of bushing 3 is slotted at 4 whereto an outlet pipe 5 is connected.

35 Threaded to bushing 3 there is a sleeve 6 held by nut 7; the forward end of said sleeve 6 is a grooved disk 6'. The sleeve 6 has reduced portions 6'' and the spaces therein are filled with an insulating material 8. Through the sleeve 6 is slidably arranged a rod 9 which is 40 partially square in cross section, as shown in Figure 11, being cylindrically shaped at the rear and having a groove 9' connected to a guiding screw 10. A spring 11 is coiled around rod 9, said rod 9 ending, as shown in Figure 11, in a stem 9'' and having a pin 12 mounted therein.

45 The lower part of rod 9, near the stem 9'', has a toothed portion 13, as shown in Figure 11, which is in mesh with a toothed block 14, pivoted at 15 to an ear 16 of a shutter plate 17 which closes the opening 4. Said block 14 is

held by a forked bracket 18 which is integral with the sleeve 6.

A nut 19 is threaded to the rear portion of bushing 3 bearing therein a packing disk 20.

The above arrangement is made to cooperate 5 with another one directly connected to the cooling water tank 21.

22 is a short horizontal pipe secured to a wall of the tank, through a washer 23, nut 23' and packing rings 24. Threaded to pipe 22 there 10 is a pipe 25, a valve 26 being set therein. Figure 10 shows in detail said valve which has longitudinal grooves 26' and a boring 27 therethrough. The front face of valve 26 is bevelled as shown in 26''.

15 Through boring 27 is mounted a rod 28 which ends in a bevelled head 29. A packing ring 30 is fitted between head 29 and block 26.

The rear end of rod 28 protrudes out from block 26 and is secured through nut 31 to spring 20 coil 32 bearing against recess 22' or pipe 22.

Pipe 25 is flanged at 25', said flange acting as a stop for two washers 33 and packing ring 34 which are loosely mounted as to provide a yieldable engagement when these parts are forced 25 against flange 25' under the strength of spring 35 coiled around pipe 25.

The operation of the device is as follows:

Assuming the different parts of the position shown in Figure 2. Upon closing the door 2, 30 the outer washer 33, under the stress of spring 35, engages with the packing 20 at the washer 19 and the forward end of pipe 25 will house into bushing 3 near to the stem 9''. The shutter 17 will close the opening 4.

35 For withdrawing water from the deposit 21 it is merely necessary to push rod 9 inwardly against the strength of spring 11, and as shown in Figure 9, stem 9'' will push inwardly valve 26 against the strength of spring 32. The water will flow 40 out from tank 21 through pipes 22 and 25 and grooves 26' to outlet 5, as in that position shutter 17 will be swung up through the meshing of the toothed portions of rod 9 and block 14; the outflow of the water being pointed out by an arrow.

Upon releasing rod 9, the strength of springs 32 and 11 will return the parts to the former position shown in Figure 5 closing the shutter 17 over the opening 4. Said closure will prevent 50 any loss of cold, especially in the event that the tank 21 and the parts attached thereto be withdrawn for purposes of repairing or refilling.

It is understood that the removing of the tank will be easily done by simply opening the door 2.

It is also understood that many changes may be made within the scope of the invention, for instance the arrangement can be made in one of the wall sides of the cabinet instead of in the door of same. In this assumption the packing 5 will be made having a protruding ring as shown in Figure 8, in order to provide a tight closure.

I claim:

10 In a faucet, a pipe, a spring-controlled valve within said pipe, a support independent of said

pipe, a spring-controlled rod for opening said valve slidably mounted in said support, said support being separable from said pipe, yieldable spring-controlled sealing means interposed between said support and said pipe to prevent escape of liquid when said pipe and support are in engagement and when said valve is opened, a discharge pipe, a shutter plate for closing said discharge pipe, and means for actuating said shutter plate when said rod is operated. 5

10 JOSÉ VIDAL BOSQUE.
